U.S. Cl. D7—121

FIG. 1.

FIG. 4.

FIG. 1 is a top plan view of a cooking platform for electric ranges and the like, embodying our new design, with the indicia as shown in FIG. 2 omitted adjacent the four rectangular areas for convenience of illustration;

FIG. 2 is a plan view of a fragmentary corner portion of the platform as shown in FIG. 1, and enlarged relative to FIG. 1;

FIG. 3 is a fragmentary horizontal section corresponding to one taken along the line III—III of FIG. 2;

FIG. 4 is a fragmentary horizontal section corresponding to one taken along the line IV—IV of FIG. 2.

The bottom face of the cooking platform, which is unornamented, is hidden from view in normal use.

We claim:

The ornamental design for a cooking platform for electric ranges and the like, substantially as shown and described.
